Silas LeSweet
ATTORNEY

UNITED STATES PATENT OFFICE.

GLEN C. MYERLY, OF DEEP RIVER TOWNSHIP, POWESHIEK COUNTY, IOWA.

WAGON END GATE AND SCOOP BOARD COMBINED.

Application filed April 24, 1925. Serial No. 25,715.

An object of this invention is to provide an improved construction for combined end-gates and scoop-boards employing a relief wicket and means for securing the wicket in closed position.

5 A further object of this invention is to provide means for supporting the wicket-holding means in open position.

10 A further object of this invention is to provide improved means for attaching the relief wicket to the scoop-board.

15 My invention consists in the construction, arrangement and combination of elements hereinafter set forth, pointed out in the claims and illustrated by the accompanying drawing, in which—

20 Figure 1 is an outside elevation of the complete device in closed position. Figure 2 is a side elevation of the same. Figure 3 is a vertical section on the indicated line 3—3 of Figure 1, the dotted lines indicating movement of the relief wicket. Figure 4 is a detail horizontal section on the indicated line 4—4 of Figure 1.

25 In the construction of the device as shown the numeral 10 designates the body or main portion of the end-gate or scoop-board, which is provided with transverse parallel spaced cleats 11, 12 and 13 on its outer face 30 and side wings 14, 15 on its inner face at right angles to the cleats. The wings 14, 15 extend below the body 10 and are adapted to engage a cross-bar (not shown) on the rear end of a wagon box in the usual manner.

35 Holes are formed in the body 10 between the wings 14, 15 and above the cleat 12 and wear plates 16, 17 are mounted on said body and are formed with holes registering with the first holes. Hook plates 18, 19 are adapted 40 to be mounted on the sides of the wagon box and extend rearwardly therefrom through the registering holes in the body 10 and wear plates and rods 20, 21 are pivoted at one end each in the outer end of one of said plates.

45 The rods 20, 21 are formed with eyes on their outer ends of such size as not to pass through the holes in the wear plates and body. Each rod 20, 21 is adapted to engage both plates 18, 19 and together hold the end-gate in closed position against the rear ends 50 of the sides of the wagon box. Also, said rods may be extended rearwardly from the wagon box and permit the end-gate to be moved through an arc into an inclined position, the body and wear plates passing longi-

tudinally of the rods until stopped in inclined position by engagement of the hooks on the outer ends of the rods with the wear plates. In the inclined position the end-gate may be used as a scoop-board. An opening 60 or notch is formed in the lower portion of the body 10 and a relief wicket 22 is formed to close said opening, the cleat 13 being cut transversely in two places and the central portion thereof being employed as a transverse cleat for the lower end portion of said wicket. Another transverse cleat 23 is mounted on the upper outside portion of the wicket 22 and spaced from the cleat 12. The adjacent margins of the cleats 12 and 23 are 70 beveled to permit the wicket to be placed at an angle to the plane of the body 10. Rabbets 24, 25 are formed in the inner faces of the cleats 12 and 23 respectively and hinges 26, 27 are mounted in said rabbets and fixed 75 to the cleats, the barrels of said hinges being between said cleats. A hook 28 is mounted on one end portion of the cleat 13 and is spaced from the rear face thereof. The hook 28 is formed as an angle plate, one flange 80 thereof extending beneath the cleat 13 and being secured thereto by bolts 29 and the other and longer flange thereof extending across and spaced from the rear face of the cleat and slightly above it and being slightly 85 curved outwardly at its upper end. A latch bar 30 is pivoted at one end on a bolt 31 at the left end of the cleat 13 and normally extends along the rear face of the cleat 13 and has its opposite end between said cleat 90 and the hook 28. A knob 32 is mounted on the latch bar 30 adjacent to the hook 32. The latch bar 30 engages that portion of the cleat 13 which extends across the lower portion of the wicket 22 and serves to hold the 95 wicket in closed position. The latch bar 30 may be moved through an arc to open position, as indicated by dotted lines in Figure 1, by manual force applied to the knob 32 and, when in said position, the bar is withdrawn 100 from the wicket and permits the wicket to be moved through an arc rearwardly, articulating on the pins of the hinges 26, 27. A spring clip 33 is fixed at one end to the rear face of the cleat 12 and 105 extends along said cleat toward the center of the body 10. The central portion of the clip 33 is offset rearwardly to receive and retain the otherwise free end of the latch bar 30 at times and hold said bar in open position. 110

tion as shown by dotted lines in Figure 1. The inner end portion of the clip 33 is inclined outwardly to receive and guide the free end portion of the latch bar beneath the clip and an inclined intermediate portion 34 of the clip facilitates removal of the latch bar therefrom manually at times when it is desired to move the bar to closed position.

10 The wicket is held in closed position at all times except when the contents of the wagon are to be dumped. When the wagon is placed in dumping position (the box thereof being inclined with its front end uppermost), the latch bar 30 is moved manually to open position, thus releasing the wicket and permitting it to assume a position at an angle to the body 10 as suggested by dotted lines in Figure 3, whereupon the 15 contents of the wagon box will flow through the notch or opening in the body and discharge thereby from the box.

I claim as my invention—

1. A combined end-gate and scoop-board, 25 comprising a body formed with a notch in its lower end portion, a wicket mounted on the body and adapted to close said notch, said body and wicket being formed with adjacent cleats, which cleats are beveled on 30 adjacent sides and rabbeted in the faces at angles to said bevels, hinges mounted in said rabbets and fixed to said cleats and means

for connecting said wicket to the body auxiliary to said hinges.

2. A combined end-gate and scoop-board, 35 comprising a body formed with parallel cleats, said body being formed with a notch in its lower end portion intersecting one of said cleats, a wicket hinged to an intermediate cleat and adapted to close said notch, said 40 wicket being formed with a cleat alining with portions of the intersected cleat, an upwardly-opening hook fixed to and spaced from one portion of the intersected cleat, and a latch bar pivoted to the other portion of 45 said intersected cleat and adapted to extend across and engage the cleat on the wicket and be engaged by said hook.

3. A combined end-gate and scoop-board, 50 comprising a body formed with cleats, said body being formed with a notch in its lower end portion intersecting one of said cleats, a wicket adapted to close said notch at times and hinged to one of said cleats, said wicket carrying the central portion of the intersected cleat, a hook fixed to and spaced from one end portion of the intersected cleat, and a latch bar pivoted to the opposite end portion of said intersected cleat and adapted to 55 extend across the central portion of said intersected cleat and across the lower end portion of said wicket and be engaged by said hook.

GLEN C. MYERLY.
